PROCESS OF TREATING TALL OIL

Ernest Segesemann, Newark, N. J., assignor to
 National Oil Products Company, Harrison, N. J.,
 a corporation of New Jersey

No Drawing. Application July 7, 1938,
 Serial No. 217,974

14 Claims. (Cl. 260—103)

The invention relates in general to the refining of tall oil and in particular to a process of separating the fatty acids from the resin acids normally present in tall oil.

5 "Tall oil" or "talloel" which literally means "pine oil" is the resinous and fatty by-product obtained in the production of paper pulp from resin-bearing woods by the so-called sulphate process. In the sulphate process wood is digested with an alkaline liquor containing sodium sulphate during which operation tall oil and soaps thereof accumulate on the surface of the waste-liquors. The main constituents of this oil after acidification comprise fatty acids and resinic acids each of which are valuable commodities in substantially pure form. Various processes have been proposed in an attempt to effect a separation of tall oil into its main constituents, i. e. fatty acids and resin acids. One process comprises 10 esterifying the fatty acids in tall oil with a low boiling alcohol and separating the resulting fatty ester from the free resin acids by alkali extraction or by distillation. Another known process comprises esterifying the fatty acids with a poly- 15 hydric alcohol and distilling off the free resin acids. According to another process both the fatty acids and the resin acids are esterified with a polyhydric alcohol and the resin esters are then catalytically split and the liberated resin acids 20 distilled off. While the foregoing and other known processes have been employed with varying degrees of success, the fact remains that only a partial separation is effected thereby. The resulting fatty acids and their esters are invariably 25 contaminated with appreciable quantities of resin acids.

The general object of the invention is to obviate the foregoing and other disadvantages.

30 A specific object of the invention is to provide a process of recovering from tall oil both the fatty acids and the resin acids, each in a substantially pure and uncontaminated state.

35 A further object of the invention is to provide an improved and more efficient process of separating the main constituents in tall oil.

40 Other objects will in part be obvious and will in part appear hereinafter.

45 It has now been found that a more complete separation of tall oil into its fatty and resinous constituents can be effected according to the invention by first subjecting the fatty acids in tall oil to the esterifying action of an alcohol of the kind that will result in esters of relatively high vapor pressure and esterifying the resin acids 50 with a different alcohol of the type that produces

esters of low vapor pressure. The resulting mixture comprises relatively low boiling fatty acid esters and higher boiling resin esters. The fatty acid esters may be distilled off under reduced pressure from the resin esters with or without the use of steam distillation. The fatty acid esters thus obtained are practically free from contamination with resin acids or esters thereof which remain in the still.

5 The invention accordingly comprises the several steps and the relation of one or more of such steps with respect to each of the others thereof, which will be exemplified in the process herein-after disclosed, and the scope of the invention will be indicated in the claims.

10 In carrying out the process of the invention the tall oil to be treated may be in the crude or partially or completely refined state. Any suitable relatively low boiling alcohol having a low carbon content preferably not more than 5 carbon atoms may be used in the esterification of the fatty acids. Examples of such alcohols include, inter alia monohydric alcohols such as the methyl, ethyl, propyl, isopropyl, butyl, isobutyl, etc. alcohols. For the esterification of the resin acids, it is preferred to employ polyhydric alcohols, such as glycerol, glycol, diethylene glycol, triethylene glycol, propylene glycol, sorbitol, mannitol or any other alcohol that will produce resin esters having a boiling point sufficiently high with 20 respect to that of the fatty acid ester formed to permit a complete separation of the latter by distillation. While any suitable polyhydric alcohol 25 may be used, it is highly preferred to employ glycerol for various reasons including cost and 30 efficiency of operation.

35 During the step of esterifying the fatty acids, suitable catalysts, such as sulfuric acid, hydrochloric acid, naphthalene- β -sulfonic acid or the like may be used. Esterification of the resin acids 40 may be carried out without the use of a catalyst, but it is preferred to accelerate the reaction by addition of such catalyzing agents as finely divided zinc, tin, zinc oxide, magnesium oxide or the like.

45 For a fuller understanding of the nature and objects of the invention, reference should be had to the following examples which are given merely to further illustrate the invention and are not to be construed in a limiting sense, all parts given 50 being by weight:

Example I

100 parts of a distilled tall oil with a rosin content of 17% are refluxed for 3 hours with 16 parts 55

of methyl alcohol and 3 parts of sulfuric acid. The excess alcohol is then distilled off at reduced pressure and the product of reaction consisting of a mixture of methyl esters of fatty acids and 5 of free resin acids is washed free from sulfuric acid. 3 parts of glycerol of 98% strength are then added and the mixture is heated at 280° C. for 8 hours. At the end of this period the acid value has dropped below 2.0. The methyl esters 10 of the fatty acids are then distilled off at a pressure of 2 mm. mercury between 145° and 165° C. The methyl esters consist of a straw-colored liquid, are substantially free from rosin and have an acid value of 1.9. They may be used as such 15 in the various industries or they may be split into their fatty acids, or they may be sulfated, phosphated or hydrogenated according to known procedures. The still residue consisting mainly of glycerides of the resin acids is a viscous brown 20 colored oil having an acid value of 0.45.

Example II

Gaseous hydrochloride is passed into 30 parts of ethyl alcohol until a solution of 5% thereof in 25 the alcohol is obtained. 100 parts of crude tall oil having a rosin content of 37.5% are then added and the mixture is refluxed for 5 hours to effect esterification of the fatty acids. The excess alcohol is then distilled off under reduced pressure. 30 6.5 parts of glycerol of 90% strength and .3 part of zinc oxide are then added and the mixture is heated under an atmosphere of CO₂ at 235° to 240° C. for 6 hours. The ethyl esters of the fatty acids are then distilled off at 15 mm. mercury between 200° and 220° C. 35

Example III

100 parts of a distilled tall oil having a rosin content of 23% are refluxed with 60 parts of n-butyl alcohol and 5 parts of naphthalene- β -sulfonic acid for 8 hours. The excess butyl alcohol is then distilled off at reduced pressure and the naphthalene sulfonic acid is washed out of the mixture. 4 parts of glycerol of 90% strength and .3 part of magnesium oxide are then added and the mixture is heated between 260° to 270° C. for 45 6 hours or until the acid value has dropped below 5.0. The butyl esters of the fatty acids are then distilled off at a pressure of 3 mm. mercury between 200° and 215° C. 50

50 While the present invention is particularly adapted for the treatment of tall oil, it is within the purview of the invention to employ the process for separating resin acids and fatty acids present in any mixture.

55 Since certain changes may be made in carrying out the above process without departing from the scope of the invention, it is intended that all matter contained in the above description shall be interpreted as illustrative and not in a limiting 60 sense.

65 It is also to be understood that the following claims are intended to cover all the generic and specific features of the invention herein described, and all statements of the scope of the invention, which as a matter of language might be said to fall therebetween.

Having described my invention, what I claim as new and desire to secure by Letters Patent is:

70 1. In a process of treating tall oil to separate the fatty acid components from the resin acid components the steps which comprise esterifying the fatty acids with a low boiling alcohol and subsequently esterifying the resin acids with an alcohol having a higher boiling point than the 75 first alcohol.

2. In a process of treating tall oil to separate the fatty acid components from the resin acid components, the steps which comprise esterifying the fatty acids with a monohydric alcohol and subsequently esterifying the resin acids with a 5 polyhydric alcohol.

3. A process of treating tall oil to separate the fatty acid components from the resin acid components which comprises esterifying the fatty acids with a low boiling alcohol, esterifying the 10 resin acids with an alcohol having a higher boiling point than the first alcohol and distilling off the fatty acid esters thus formed.

4. A process of treating tall oil to separate the fatty acid components from the resin acid components which comprises esterifying the fatty acids with a monohydric alcohol, esterifying the resin acids with a polyhydric alcohol and distilling off the fatty acid ester thus formed. 15

5. A process of treating tall oil to separate the 20 fatty acid components from the resin acid components which comprises esterifying the fatty acids with a monohydric alcohol in the presence of an acid catalyst, esterifying the resin acids with a polyhydric alcohol and distilling off the 25 fatty acid ester thus formed.

6. A process of treating tall oil to separate the fatty acid components from the resin acid components which comprises esterifying the fatty acids with methyl alcohol in the presence of an 30 acid catalyst, esterifying the resin acids with a polyhydric alcohol and distilling off the fatty acid ester thus formed.

7. A process of treating tall oil to separate the fatty acid components from the resin acid components which comprises esterifying the fatty acids with ethyl alcohol in the presence of an acid catalyst, esterifying the resin acids with a polyhydric alcohol and distilling off the fatty acid ester thus formed. 35

8. A process of treating tall oil to separate the fatty acid components from the resin acid components which comprises esterifying the fatty acids with a butyl alcohol in the presence of an acid catalyst, esterifying the resin acids with a 45 polyhydric alcohol and distilling off the fatty acid ester thus formed.

9. A process of treating tall oil to separate the fatty acid components from the resin acid components which comprises esterifying the fatty acids with a monohydric alcohol having not more 50 than 5 carbon atoms in the presence of an acid catalyst, esterifying the resin acids with glycerol and distilling off the fatty acid ester thus formed.

10. A process of treating tall oil to separate the fatty acid components from the resin acid components which comprises esterifying the fatty acids with methyl alcohol in the presence of an acid catalyst, esterifying the resin acids with glycerol and distilling off the fatty acid ester thus 60 formed.

11. A process of treating tall oil to separate the fatty acid components from the resin acid components which comprises esterifying the fatty acids with ethyl alcohol in the presence of an acid catalyst, esterifying the resin acid with glycerol and distilling off the fatty acid ester thus 65 formed.

12. A process of treating tall oil to separate the fatty acid components from the resin acid components which comprises esterifying the fatty acids with a butyl alcohol in the presence of an acid catalyst, esterifying the resin acids with glycerol and distilling off the fatty acid ester thus 70 formed.

13. The process of separating the fatty constituents from the resinous constituents of tall oil which comprises esterifying the fatty acids with an alcohol of the group that produces fatty acid esters of relatively high vapor pressure, esterifying the resin acids with an alcohol of the type that produces resin esters of low vapor pressure with respect to that of the fatty acid esters and separating the fatty acid esters by distillation.

14. A process of recovering the fatty components from a mixture containing fatty acids and resin acids which comprises esterifying the fatty acids with a monohydric alcohol having no more than 5 carbon atoms, esterifying the resin acids with a polyhydric alcohol and recovering the fatty acid esters thus produced by distillation. 5

ERNEST SEGESSEMANN.
